US00D485755S

(12) **United States Design Patent** (10) Patent No.: **US D485,755 S**
 Isler et al. (45) Date of Patent: ** Jan. 27, 2004

(54) **BAKING CONTAINER**

(75) Inventors: **Letesa R. Isler**, Waukegan, IL (US);
Matthew A. McCurdy, Marysville, OH (US); **David J. Bulcher**, Powell, OH (US); **David C. Schiltz**, Columbus, OH (US)

(73) Assignee: **Pactiv Corporation**, Lake Forest, IL (US)

(**) Term: **14 Years**

(21) Appl. No.: **29/179,792**

(22) Filed: **Apr. 15, 2003**

(51) LOC (7) Cl. **09-03**

(52) U.S. Cl. **D9/425**

(58) Field of Search D7/360, 629; D9/414, D9/424, 425, 430, 431, 432, 499; 206/557, 564, 515, 518, 503, 525, 527; 220/573.1, 574, 660, 669, 670, 675; 229/406, 407, 902, 903, 906, 915, 919
